Inventor:
Christian Steenstrup,
by *Christian S. Steenstrup*
His Attorney.

UNITED STATES PATENT OFFICE.

CHRISTIAN STEENSTRUP, OF SCHENECTADY, NEW YORK, ASSIGNOR TO GENERAL ELECTRIC COMPANY, A CORPORATION OF NEW YORK.

CLOSED FURNACE AND METHOD OF OPERATING THE SAME.

Application filed December 20, 1923. Serial No. 681,864.

To all whom it may concern:

Be it known that I, CHRISTIAN STEENSTRUP, a citizen of the United States, residing at Schenectady, in the county of Schenectady, State of New York, have invented certain new and useful Improvements in Closed Furnaces and Methods of Operating the Same, of which the following is a specification.

- 10 The present invention relates to closed furnaces of the type in which its operations are performed in the presence of a selected gas to prevent oxidation of the charge, and especially to such furnaces when internally 15 heated by electrical means. Briefly stated, such furnaces comprise a closed metal vessel or container heavily lined with heat-resisting material, electrical heating units or resistors within its chamber, a conduit for 20 supplying the selected gas, and usually a restricted outlet through which a small amount of the gas continually escapes to serve as an indicator that the proper gas conditions exist within the container. The 25 temperature within the container is regulated by varying the amount of current admitted to the units or resistors, by varying the number of units or resistors in circuit, or their electrical connections, or by varying 30 all of them. Such furnaces are entirely satisfactory for many classes or kinds of work, but are open to one serious defect for other classes or work because the temperature of one or more selected portions of the 35 charge cannot be controlled or regulated independently of another or other portions. As an illustration I refer to a class or classes of work in which the furnace charge is composed of two or more pieces or parts of 40 metal which are to be united by fusion which pieces differ in mass or coefficient of expansion or heat conductivity. This can best be understood and appreciated by references to a particular kind or class of charge but 45 without limitation thereto or to the particular type of furnace construction since my invention is capable of wider application. One application of my invention which I 50 may use as an illustration is the uniting of the parts of a diaphragm or of a bucket wheel of a steam turbine by fusion, copper being the fusing metal, the operation being carried out in the presence of hydrogen gas. Briefly stated, a diaphragm comprises a

massive center member, a relatively thin annular rim, and thin, radially-extending nozzle partitions between the member and rim. A bucket wheel comprises a massive center member, a thin, annular cover and sharp edged radially-extending buckets located between the member and cover. To attain the best results the parts should be tightly fitted one to the other when cold so that there will be no appreciable spaces between parts at the joints. In other words, the spaces should be of a capillary nature. Upon heating up such a diaphragm or wheel in a closed hydrogen furnace the rim or cover, being less massive than the center member, reaches fusion temperature before the member and in so doing expands away from the partitions or buckets and causes objectionable looseness resulting in defective joints or in complete failure thereof.

In some cases I have found that the rim or cover does not heat up uniformly or if it does that one portion offers a greater resistance to movement than the remainder with the result that the part gets out of round. When such a part shrinks in cooling it does not return to its original shape with the result in some instances that there is a decided bulge at one point. Under such conditions some of the joints in a given structure will be good, some imperfect and others fail completely. It is obvious of course that a structure, particularly one intended for high rotative speeds, cannot be used if it has a single imperfect joint.

I have discovered that the above mentioned objections can be overcome and uniformly good joints obtained by regulating the temperature of one or more of the component parts of the charge within the furnace and this independently of the temperature of the furnace as a whole. To accomplish this I locate inside of the furnace one or more elements which for convenience may be termed coolers or cooling elements and which preferably conform rather closely in shape and size to that selected portion of the charge the temperature of which is to be regulated. These elements are made hollow and through them is caused to flow a suitable cooling fluid subject to the control of a regulating means such as a valve. The cooling elements may be made in different ways. For example they may be closed at

- all points except the ends which extend outside of the furnace in which case the cooling fluid flows continuously from end to end absorbing heat from the walls of the element in 5 so doing, or they may have one closed end and be provided with one or more perforations or orifices arranged to direct a stream or streams of cooling fluid against the part whose temperature is to be regulated.
- 10 The type of cooling element will be determined by the character of the fluid employed. One simple effective way to accomplish the desired result is to use a perforated element having one closed end and supply 15 to it from a suitable outside source the same kind of selected gas that is used in the furnace operation. By suitably varying the amount of fluid flowing through the cooler or coolers the heating of any particular or 20 selected part or portion of the charge can be so retarded that it will reach the fusing temperature at approximately the same time as the other or more massive part. By the same means said selected part or portion 25 can be cooled and therefore shrunk before another part and in this manner ensure uniformly good joints between those parts having different masses. Briefly stated my improvement permits of any selected part of 30 the charge being retarded in its heating and advanced in its cooling without change of temperature in the furnace itself.
- By way of example as applied to the manufacture of diaphragms or bucket wheels, I 35 locate in the furnace and in proximity to the rim or cover an annular chambered element which has a narrow slot or one or more rows of small openings or orifices through which one or more small streams of gas escape with 40 sufficient velocity to strike the surface of the rim or cover. By admitting a regulated amount of gas in this manner the heating of the rim or cover can be retarded so that it and the center member will reach fusion 45 temperature at the same time. This can be determined by the use of the usual sight openings in the furnace wall. On account of the difference in mass of the center member and rim or cover, the member cools more 50 slowly and to ensure proper hardening of the copper between the rim or cover joints and the parts to be fused thereto the supply of cool temperature controlling gas directed against them may be increased to such an 55 extent as to rapidly reduce the temperature of the rim or cover causing shrinking thereof and this before the temperature of the furnace as a whole is reduced sufficiently to cause the copper in the joints to solidify or 60 set. The shrinking of the rim or cover in the manner described completes the joints between it and the partitions or buckets which joints are sufficiently strong so that 65 when the center member cools it pulls the rim or cover inwardly with it.

Instead of leaving an open space between the cooling element and the part to be controlled when a selected gas is used as the cooling fluid and directed against said part, I may in some cases separate the controlled 70 part from the element by a small space which is filled with ordinary sand and through which the gas must pass before striking said part. The advantage of this resides in the fact that it prevents too sudden changes of temperature which might be occasioned by careless manipulation of the gas-controlling valve.

Reference has been made to causing one part to exert pressure on another by shrinking to ensure good joints, the cooling fluid absorbing heat from the member that is to be shrunk. This may be termed the direct method. The same result may also be accomplished in some instance by an indirect 80 method. For example, take the simple case of two metal blocks which are to be fused. The blocks may be mounted between two heads and the latter connected by relatively long rods or bolts. After the blocks, heads and rods which in this case form the charge are heated to fusing temperature the rods or bolts are cooled which will cause them to shrink and thus exert heavy pressure at 85 the joint between the blocks.

Since the operations in the furnace are carried out in the presence of a selected gas which must be continually supplied during the working period, it naturally follows that the best suited gas for controlling the 100 temperature of the selected portion of the charge is the same kind of gas that is used for the main or fusing operation. When this is done the main supply of gas can be cut down in proportion to the amount admitted for cooling and therefore no extra gas is required. Fresh gas may be used for cooling or gas may be withdrawn from the furnace container and after being properly cooled discharged under pressure 105 into the cooling element. It also follows where the same kind of gas is used for both purposes that small leakages from the cooling element due to faulty joints, etc., may be disregarded.

In the accompanying drawing, which is illustrative of my invention, Fig. 1 is a view in vertical section of a closed furnace and its charge; Fig. 2 is a plan view illustrating a bucket wheel or diaphragm; Fig. 3 is a perspective view of a cooling element; Fig. 4 is a view showing another form of charge and cooler; Fig. 5 illustrates another means for causing shrinkage in order to exert pressure at the joint between two parts, and Fig. 6 shows a portion of a bucket wheel and cooler on an enlarged scale.

The furnace shown in Fig. 1 is of the same general type as that described and 130

claimed in my prior application for patent, thereto. Assuming that the pin is tightly fitted or seated in the block and that heating current is admitted to the resistors of the furnace the pin owing to its lesser mass would be heated more quickly than the 71 block. Under these conditions the pin would expand more rapidly than the block and since the latter would not yield the forces exerted would cause the metal in the pin to 75 flow slightly in an axial direction. If now the parts are cooled, it will be found that whereas the original fit was tight, it is now loose. To prevent this, a cooler 19 of appropriate shape and size is provided to which a 80 cool, selected gas is admitted during the heating operation and caused to exert sufficient retarding effect on the pin so that the parts will attain fusing temperature at practically the same time. 85

Fig. 5 shows a means for exerting pressure at the joint between two parts by an indirect method. In this case the charge comprises the blocks 32 and 33 which are to be fused at the joint 34 between them, heads 35, 90 the connecting rods 36 and the fusing metal which should be placed over the joint. Between the heads and blocks are layers of asbestos 37 or equivalent material to prevent accidental fusing between them. On one side of each rod is a cooler 19 to which a supply of cool, selected gas is admitted in regulated amount. When the blocks and fusing metal are at fusing temperature, cool gas is 95 directed against the rods which causes them to shrink and in so doing exert heavy pressure on the heads and through them similar pressure at the joint 34 after which the temperature of the furnace may be reduced in the usual way as by reducing the supply of current to the resistors, or the charge may be transferred to a cooler for this purpose. The principal distinction in this arrangement over the other is that the means which are shrunk to exert pressure form no part of 100 the finished article. 105

Between the rim 21 and the cooler it is 45 desirable to have a body of sand as shown in Fig. 1 so that careless manipulation of the gas controlling valve will not cause sudden changes of temperature in the rim. It is also desirable to cover this body of 50 sand by a shield 10^a to prevent the gas from flowing upwardly instead of horizontally against the rim. 55

In Fig. 3 is shown a perforated cooler of ring shape which surrounds the charge, 60 whatever it may be and to which a selected gas is admitted by the pipe 24 subject to the control of a regulating valve 25, 10^a representing the shield. As shown in Fig. 1 the sand container is slotted above the pipe so as to permit the furnace to be raised and lowered. 65

Fig. 4 illustrates a different kind of charge and a cooler of different shape. In this figure 30 indicates a block of steel and 31 a 70 round steel pin or shaft that is to be fused

drogen gas admitted to the chambers of the furnace by the pipe 15 subject to the control of valve 15^a.

To prevent the parts of lesser mass from heating too rapidly a selected gas such as hydrogen is admitted to the cooler 19 by pipe 24 subject to the control of valve 25. By means of the sight tubes 16^a the conditions within the furnace can be observed and the amount of cooling gas increased or decreased as conditions require. The point is to admit sufficient gas to retard the heating of the parts of lesser mass so that the whole charge will reach fusing temperature at practically the same time. As the supplies of selected gas are the same both for the normal fusing operation as well as the cooling, the main supply can be cut down in proportion to the increase of cooling gas. When fusing temperature is reached, the amount of cooling gas is increased so as to cause the parts of lesser mass to cool and thereby shrink. This same action causes the copper or fusing metal to harden and complete the joints acted upon by the gas. The temperature of the furnace as a whole may then be reduced to finish the operation or the furnace may be lifted and the charge moved to a separate container which may be water cooled and in which a supply of selected gas is maintained during the cooling operation.

What I claim as new and desire to secure by Letters Patent of the United States is:—

1. In a furnace, the combination of a closed container adapted to contain the charge, means for maintaining a supply of selected gas within the container to prevent oxidation of the surfaces of the charge during the working period, means for heating the container and its charge, and means acting independently of the heating means for controlling the temperature of a selected portion of the charge.

2. In a furnace, the combination of a closed container adapted to contain the charge, means for maintaining a supply of selected gas within the container to prevent oxidation of the surfaces of the charge during the working period, means for heating the container, and means acting independently of the heating means to retard the increase in temperature of a selected portion of the charge with respect to another as the temperature of the furnaces rises due to the heating means and to cool said selected portion in advance of the cooling of another portion.

3. In a furnace, the combination of a closed container adapted to contain the charge, means for maintaining a supply of selected gas within the container to prevent oxidation of the surfaces of the charge during the working period, means for heating the container, and a conduit entering the container and through which a selected non-

oxidizing gas is directed against a selected portion of the charge to control its temperature independently of that due to the heating means.

4. In a furnace, the combination of a closed container adapted to contain the charge, means for maintaining a supply of selected gas within the container to prevent oxidation of the surfaces of the charge during the working period, means for heating the container, and an element independent of the charge which conforms generally in shape to a selected portion thereof, is perforated, and through which a non-oxidizing gas flows for controlling the temperature of the selected portion of the charge.

5. In a furnace, the combination of a closed container which encloses the charge, means for maintaining an atmosphere of selected gas within the container during the working period, means for heating the container, a perforated element within the container which conforms generally in shape to a selected portion of the charge and is independent thereof, a conduit for supplying a non-oxidizing gas to the element, and valve means for regulating the flow of gas through the conduit and element.

6. In a furnace, the combination of a closed container which encloses the charge, a conduit for supplying a selected gas to the container during the working period to prevent oxidation of the surfaces of the charge, means for heating the container, a chambered means independent of the charge which is within the container, encloses a portion of the charge and is provided with a discharge orifice, and a conduit for supplying a selected gas under pressure to the chambered means for controlling the temperature of that portion of the charge enclosed by it.

7. In a furnace, the combination of a closed container adapted to contain the charge, comprising parts which are to be united by fusion and a fusing metal, means for maintaining a supply of selected gas in the container during the working period to prevent oxidation, means for heating the container and charge, and means acting independently of the heating means to cause shrinkage of a part of the charge with respect to another whereby pressure is exerted on the joint.

8. In a furnace, the combination of a container comprising a closed casing lined with heat-resisting material and a charge-supporting platform, a conduit for supplying a selected gas to the container during the working period, electrical heating units for the container, a means supported by a part of the container which encloses a selected portion of the charge, and discharges a stream of selected gas against the adjacent portion of the charge to locally con-

- trol its temperature, and a valve-controlled conduit for supplying a selected gas under pressure to the means.
9. In a furnace, the combination of a platform, a closed casing lined with heat-resisting material which is supported by its own weight on the platform, packing means between the platform and casing to restrict the free escape of gas, a conduit for supplying a selected gas under pressure to the casing and in regulated amounts, an electrical heating unit within the casing, a chambered means supported inside of the casing which approximately conforms in shape and size to a selected portion of the charge the temperature of which it is desired to independently control and a valve-controlled conduit for supplying a selected gas under pressure to the chambered means.
10. In a furnace, the combination of a closed container adapted to contain a charge comprising pieces of metal of differing mass and a fusing metal of lower melting point for uniting them, means for heating the charge to fusing temperature, means for maintaining a supply of a selected gas in the container during the working period to prevent oxidizing of the surfaces of the charge, and means for controlling the temperature of a piece of said charge having a lesser mass by directing a stream of selected gas against it.
11. In a furnace the combination of a closed container adapted to contain a charge comprising pieces of metal which expand and contract by different amounts in the same period of time and a fusing metal of lower melting point for uniting them, means for heating the charge to fusing temperature, means for maintaining a supply of selected gas in the container during the working period to prevent oxidizing of the surfaces of the charge, means for directing a stream of selected gas against that piece of the charge which has a tendency to expand more rapidly than the other to retard said tendency, and a regulator for said means.
12. In a furnace, the combination of a closed container adapted to contain a charge comprising separate pieces of metal which are to be joined by fusion and a fusing metal, means for heating the container and charge to fusing temperature, a conduit for supplying a selected gas to the container during the working period to prevent oxidizing of the surfaces of the charge, and a controllable cooling means for causing pressure to be exerted at the joint between the pieces prior to reducing the temperature of the container.
13. The method of uniting separate pieces of metal by fusion which comprises placing the charge comprising said pieces and a fusing metal of lower melting point in a closed container, heating the container and charge above the melting point of the fusing metal, applying pressure to the pieces when hot through the medium of a cooling fluid to ensure good contact at the joint between them, and reducing the temperature of the charge to permit the fusing metal to harden.
14. The method of operating a closed furnace which comprises charging the furnace, heating the furnace and its charge to working temperature, supplying a selected gas to the furnace to prevent oxidation of the charge, and supplying an additional amount of selected gas to the furnace in such manner as to control the temperature of a selected portion of the charge.
15. The method of operating a closed furnace which comprises charging the furnace, heating the furnace to working temperature, maintaining a supply of selected gas in the furnace, regulating the temperature of a selected part of the charge by discharging a selected gas against it, and varying the main supply of selected gas approximately in proportion to the variations in the amount of gas supplied for temperature-regulating purposes.
16. The method of uniting separate pieces of metal of differing mass by fusion which comprises placing the charge comprising said pieces and sufficient fusing metal having a lower melting point to fill the joints between them in a closed container, heating the charge to a point above the melting temperature of the fusing metal, maintaining a supply of selected gas within the container during the working period to prevent oxidizing of the charge, and controlling the temperature of a selected portion of the charge independently of the remainder by directing a stream of selected gas against it.
17. The method of operating a closed furnace which comprises placing the charge within the furnace, supplying heat to the furnace until the charge attains the desired temperature, maintaining a supply of selected gas within the furnace to prevent oxidation of the charge, retarding the heating of a selected portion of the charge as the temperature of the furnace increases, and cooling said selected portion in advance of the remaining portion.
18. In a furnace, the combination of a sealed container in which the charge is enclosed, conduit means for maintaining within the container an atmosphere of selected gas during the working period to prevent oxidation of the surfaces of the charge, means for heating the container and its charge, and conduit means for introducing a non-oxidizing gas into the container in such manner as to control the changes of temperature of a selected part of the charge.
19. In a furnace, the combination of a

sealed container which entirely encloses the charge, means for maintaining within the container an atmosphere of non-oxidizing gas during the working period, means within the container for heating it and the charge to operating temperature, and means for introducing an additional supply of the same selected gas into the container in such manner as to control the temperature of a selected part of the charge independently of the changes due to the heating means.

20. A furnace comprising a closed con-

tainer, means for maintaining therein a supply of selected gas to prevent oxidation of the surfaces of the charge, a perforated cooler located within the container which encloses a portion of the charge undergoing treatment, and conduit means for supplying to the cooler the same kind of selected gas which is supplied to the container by the first mentioned means. 15 20

In witness whereof, I have hereunto set my hand this 19th day of December, 1923.

CHRISTIAN STEENSTRUP.
